AUTOMATIC PACKAGE BANDING OR STRAPPING MACHINE

Arthur J. Brown, Bronx, N. Y., Charles F. Osgood, Jr., Ridgewood, N. J., and William M. Grosvenor, Jr., New York, N. Y., assignors to General Strapping Corporation, New York, N. Y., a corporation of New York

Application June 30, 1950, Serial No. 171,522

23 Claims. (Cl. 100—27)

This invention relates to an automatic package banding or strapping machine which is designed to wrap a metallic ribbon-like band around a package, tension the band, sever the band with its ends overlapped, and unite the said overlapped ends by welding.

Generally speaking the invention is directed to improvements and advances in, to and upon the machine disclosed in United States patent to John James Cheesman numbered 2,367,168, dated January 9, 1945, and application for United States patent filed by said John James Cheesman on October 29, 1946, under Serial Number 706,445, which issued as Patent No. 2,614,487 on October 21, 1952.

An object of the invention is to provide novel means for feeding the band from a source of supply to the machine which automatically insures an adequate and proper supply for each banding operation regardless of the size and/or shape of the package being bound, and also avoids any condition tending to disturb the desired tension under which the band is wrapped around the package.

Another object is to provide such a machine in which there is automatically maintained a surplus or slack in the band intermediate its source of supply and the elements which are applying it to the package, and in which the maintenance of this surplus or slack, as well as its amount, is governed by the said excess or slack portion of the band itself which activates and deactivates a controlling device such, for instance, as an electric eye or a micro or limit switch.

Another object is to provide such a machine which embodies improved and efficient mechanism for activating and determining the sequence of operation of the band applying, gripping, tensioning, severing and welding devices to insure rapid, uniform and reliable functioning of the machine for its intended purpose; and to enable the machine to perform equally well when packages of the same or different sizes and shapes are presented seriatim to the machine for banding.

Another object is to provide such a machine which is well fitted for cooperation with package delivery and removing apparatus such, for instance, as traveling belts; whereby a line of packages may be delivered to the machine, banded by the machine, and removed therefrom in a continuous process and without substantial interruption.

Another object is to provide such a machine which embodies a single cam shaft that is driven intermittently for single revolutions of 360 degrees and in each such revolution, by means of cams fixed thereon, activates the operative functional results of the machine in proper sequence and for properly timed periods.

Another object is to provide such a machine in which the said cam shaft carries a cam that activates and controls the feeding of the leading end of a band to the welding position and to a holding gripper, as well as the final tensioning of the band around the package; and which also carries additional cams for activating and controlling the closing and opening of the grippers, the operation of the

2

band severing cutter, and the operation of the welding electrodes.

Another object is to provide such a machine which includes novel and effective mechanism for activating and controlling the feeding and tensioning gripper during that portion of its operative cycle from the moment it releases its grip upon a band that is about to be welded to the moment when it grips the leading end of a succeeding band; in which portion of its cycle of operation the said gripper moves laterally away from the line along which the band is fed to the machine, rearwardly toward the source of band supply and parallel to said line of band feed, and then laterally back to said line.

Another object is to provide such a machine in which the gripper for holding the band under tension and the electrodes for welding the overlapped ends of the band are fitted with means for insuring adequate force or power in their operative functional movements without impairing the cam shaft cycle of operations.

Another object is to provide such a machine which includes means for regulating, either mechanically or electrically or by a combination thereof, the duration of the welding contact of the electrodes to insure a firm uniting of the overlapped ends of the band under varying operative conditions including size and shape of package and thickness and composition of band.

Another object is to provide such a machine in which the band severing device includes means for crimping the band at the time it is severed in order to provide a formation at the extremity of the leading end of the following band material to prevent it from interfering with any part of the machine or with the overlap of the previously formed band, and in which there is also means for slightly bending the band at the overlap to accommodate the cut off end.

Another object is to provide such a machine in which the band that accumulates on the ring is carried by supporting elements so closely spaced that the band is held in substantially circular form.

Another object is to provide certain improvements in the form, construction and arrangement of the parts whereby the above named and other objects inherent in the apparatus may be effectively attained.

A practical embodiment of the invention is represented in the accompanying drawings, in which:

Fig. 1 represents a broken front elevation of the machine, partly in section;

Fig. 2 represents a detail top plan view of the band feeding elements;

Fig. 3 represents a vertical section, partly in elevation, taken in the plane of the line III—III of Fig. 2, looking in the direction of the arrows;

Fig. 4 represents a broken side elevation of the machine;

Fig. 5 represents an enlarged detail elevation on the line V—V of Fig. 4, looking in the direction of the arrows;

Fig. 6 represents an enlarged detail section taken in the plane of the line VI—VI of Fig. 1, looking in the direction of the arrows;

Fig. 7 represents an enlarged detail section taken in the plane of the line VII—VII of Fig. 1, looking in the direction of the arrows;

Fig. 8 represents an enlarged detail section taken in the plane of the line VIII—VIII of Fig. 1, looking in the direction of the arrows;

Fig. 9 represents an enlarged detail section taken in the plane of the line IX—IX of Fig. 1, looking in the direction of the arrows;

Fig. 10 represents an enlarged detail front elevation of the machine showing a box almost completely banded, with the operating parts in position to tension the band;

Fig. 11 represents a similar view with the operating parts in the position following tensioning of the band; the auxiliary holding gripper having seized the end of the tensioned band to hold it under tension; the cutter and crimper being about to sever and crimp the band, and the feeding and tensioning gripper having gripped the leading portion of a succeeding band.

Fig. 12 represents a similar view, the cutter and crimper having completed their operation and the welding elements being in position to unite the overlapped ends of the severed band.

Fig. 13 represents a side elevation of the lower portion of the band after it has been welded;

Fig. 14 represents a detail plan view, partly in section, of the foot pedal and associated parts for controlling the clutch mechanism;

Fig. 15 represents a front elevation of the same, looking from right to left in Fig. 14;

Fig. 16 represents a vertical section taken in the plane of the line XVI—XVI of Fig. 14, looking in the direction of the arrows, and also showing part of the motor drive;

Fig. 17 represents a detail section, partly in elevation, of the main drive and clutch mechanism;

Fig. 18 represents a detail vertical section, partly in elevation and partly broken away, more completely showing the said drive and clutch mechanism with the associated retractable band guiding finger;

Fig. 19 represents a top plan view, partly broken away, of the parts shown in Fig. 18;

Fig. 20 represents an end elevation of the same, looking from left to right in Figs. 18 and 19, together with the motor, drive belt, and part of the package supporting casing top;

Fig. 21 represents a broken top plan view of the cam shaft and band feeding and tensioning cam, with associated parts, which actuate the gripping, feeding, tensioning, severing and welding elements, together with the transformer and welding electrodes;

Fig. 22 represents a detail end elevation, looking from left to right in Fig. 21, and showing the micro switch and its cam for initiating and controlling the welding period;

Fig. 23 represents a detail horizontal section, partly in elevation, of the band feeding and tensioning cam and associated parts, with the elements in a position different from that shown in Fig. 21;

Fig. 24 represents a vertical section taken substantially in the plane of the line XXIV—XXIV of Fig. 23, looking in the direction of the arrows;

Fig. 25 represents a vertical section taken in the plane of the line XXV—XXV of Fig. 24, looking in the direction of the arrows;

Fig. 26 represents a layout of the band feeding and tensioning cam and its groove;

Fig. 27 represents a vertical section, partly in elevation, taken in the plane of the line XXVII—XXVII of Fig. 21, looking in the direction of the arrows;

Fig. 27a represents a detail horizontal section taken in the plane of the line XXVIIa—XXVIIa of Fig. 27, looking in the direction of the arrows;

Fig. 27b represents a front elevation of the parts shown in Fig. 27a;

Fig. 28 represents a detail vertical section of part of the elements shown in Fig. 27;

Fig. 29 represents a vertical section more clearly showing certain parts which are partly hidden in Fig. 27;

Fig. 30 represents a broken detail plan view of the first band holding gripper and its actuating mechanism;

Fig. 31 represents a vertical section taken in the plane of the line XXXI—XXXI of Fig. 30, looking in the direction of the arrows;

Fig. 32 represents a similar view with parts shown in different positions;

Fig. 33 represents a broken detail plan view of the aux-

iliary band holding gripper and band severing cutter with their actuating mechanism;

Fig. 34 represents a vertical section taken in the plane of the line XXXIV—XXXIV of Fig. 33, looking in the direction of the arrows;

Fig. 34a represents a detail elevation of a modified and preferred form of actuating rod for the auxiliary band holding gripper;

Fig. 35 represents a detail vertical section taken in the plane of the line XXXV—XXXV of Fig. 33, looking in the direction of the arrows, and more clearly showing the band severing cutter with its actuating mechanism;

Fig. 36 represents a detail vertical section more clearly showing the mechanism for increasing the power of the auxiliary band holding gripper;

Fig. 37 represents a detail front elevation of the band feeding and tensioning gripper, with its actuating mechanism;

Fig. 38 represents a plan view of parts shown in Fig. 37;

Fig. 39 represents a side elevation thereof, partly in section;

Fig. 40 represents a detail vertical section more clearly showing certain of the parts disclosed in Fig. 39;

Fig. 41 represents a detail side elevation, partly in section, of a portion of Fig. 39, with the gripper and its immediately associated parts in positions different from Fig. 39;

Fig. 42 represents a detail side elevation, partly in section, of another portion of Fig. 39, more clearly showing certain of the parts;

Fig. 43 represents a rear elevation of the parts shown in Fig. 42, one element being partly broken away more clearly to disclose those behind it;

Figs. 44 through 52 graphically represent, with inscriptions, an illustrative sequence of operative effects as they occur during one complete 360 degree revolution of the cam shaft; and

Fig. 53 represents a wiring diagram illustrating the machine controls.

As pointed out in the patent and application hereinabove identified, this machine includes a ring which is driven in an anti-clockwise direction and wraps the band around a package positioned within the ring while the band at the same time accumulates on the ring. It will be clear that different lengths of band are used in wrapping packages of different sizes and, as it is important that there shall neither be a shortage of nor too great an excess of band available for wrapping different sized packages as they are presented to the machine, and as it is likewise important that the band shall be wrapped around each package under substantially uniform tension, the machine of the present invention is provided with means for automatically insuring accomplishment of the said important functions through controlling the supply and feeding of the band from a reel or spool of band material.

Referring particularly to Figs. 1 to 3 of the drawings, a reel or spool of band material is denoted generally by 1 and is mounted for rotation in a frame 2, 2, which may be located adjacent the machine and substantially in line with the mechanism which wraps the band around the package. The frame 2, 2, carries four arms, indicated generally by 3, at each side of the reel to hold the latter against lateral displacement, and the axle 4 on which the reel is mounted is provided with a brake drum 5 that is embraced by a pair of brake shoes 6, 6, the lower ends of which are pivoted in a crossbar 7 that is fixed to the frame below the drum 5 while the upper ends of the shoes are connected by suitable linkage, denoted generally by 8, with a solenoid 9 that is subject to activation in the usual way for tightening and releasing the shoes with respect to the drum. As such brake construction is well understood by mechanics, further detailed description is regarded as unnecessary, but it may

be added that the brake shoes may be made spring actuated and released by the solenoid if preferred.

A pair of feed rolls 10, 11, are journaled one above the other in bearings formed in the sides of a box 12 that is mounted on a platform 13, or in any other appropriate manner, intermediate the reel frame 2, 2, and the machine; the lower roll being connected with means, denoted generally by 14, such, for instance, as a slide backed by an eccentric, for moving the roll upwardly and downwardly with respect to its mate 10; a handle 15 being provided for this purpose. The said rolls are fitted with intermeshing gears 16, 17, gear 16 being fixed to the shaft of a motor 18, with the intervention of a clutch mechanism 19 that is subject to clutching operation by a solenoid 20 and de-clutching by a spring 21, as clearly shown in Fig. 2. As this clutch mechanism is conventional, there is deemed to be no occasion further to describe it other than to say that activation of the solenoid 20 in the customary manner closes the clutch 19 and causes the gears 16, 17, to be driven by motor 18 for positively rotating feed rolls 10, 11, while the deactivation of the solenoid permits the spring 21 to open the clutch. It may here be mentioned that the electric circuits to solenoids 9 and 20 are so arranged that, when solenoid 20 is activated solenoid 9 is deactivated, and vice versa; whereby brake shoes 6, 6, release brake drum 5 when feed rolls 10, 11, are driven so as to permit rotation of reel 1, while with the stoppage of feed rolls 10, 11, through opening of clutch 19, the brake shoes seize drum 5 to stop rotation of reel 1 and prevent overthrow of the metallic band from the reel. In other words, the electrical and mechanical linkages are so arranged that, when the feed rolls 10, 11, are actually driven, the reel 1 is not subjected to braking action so that it may rotate to supply the band and, vice versa, when the feed rolls are not driven, a brake is applied to stop the rotation of the reel.

An idler guide roll 22 is journaled for free rotation in a pair of uprights 23, 23, that are fixed on the platform 13 so that the band, marked B, may be passed thereunder and given an upward lead to the bight between feed rolls 10 and 11, thereby causing the band to contact more of the surface of roll 11 and increase the drawing effect of the latter.

An elongated horizontally disposed suitably supported magazine 24 is positioned with one end communicating with an opening 25 formed in one side of box 12 and extends therefrom beneath the machine, as clearly shown in Figs. 1 and 3. This magazine 24 and the box 12 with which it is associated may be composed of sheet metal or any other proper material. An idler band guide roll 26 is mounted at the top of the box 12 and near the edge of the latter which is toward the machine, and another guide roll 27 is fixed to the machine frame. The other end of magazine 24 traverses the casing of an electric eye unit, which is diagrammatically illustrated and marked 28. The casing of the electric eye is mounted on any suitable support (not shown) and the end of the magazine which traverses it is provided with an opening 29 so that the eye may be affected by the presence or absence of an object within the magazine. As such an electric eye unit is a well known device available to designers generally, there appears to be no occasion for illustrating or describing its structure; but it needs to be pointed out that the said eye is connected by appropriate electric circuits (not shown) with solenoids 9 and 20 so that, when the electric eye is activated, it will thereupon activate solenoid 20 and deactivate solenoid 9 and, when the electric eye is deactivated by the interpositioning of an object between its functional elements, solenoid 20 will be deactivated and solenoid 9 activated.

When preparing to put the machine in use, the band B is manually led from reel 1 underneath idler roll 22 and between driven rolls 10, 11, the latter being temporarily slightly depressed by handle 15 to permit a

ready passage of the band between said rolls. The band is then fed into a loop into magazine 24 for a distance terminating at some point between box 12 and electric eye 28, as indicated for instance in dotted lines and marked C in Fig. 1. The free end of the band is then led around guide rolls 26, 27, and threaded into the machine, as will be hereinafter described. When the electric current is turned on for the operation of the machine, solenoid 20 is activated by electric eye 28 because the band in magazine 24 is in approximately the position marked C and there is nothing to interrupt the beam of the eye. This activation of solenoid 20 closes clutch 19 and causes motor 18 to rotate feed rolls 10, 11, so that the band is fed into the magazine 24 by the said rolls. It will be understood that, at this time, brake shoes 6, 6, are not restraining drum 5 because, as previously mentioned, solenoid 9 is deactivated when solenoid 20 is activated. Thus the operation of feed rolls 10, 11, will continue to feed the band into the magazine 24 until it reaches the position substantially as shown in full lines and marked D, at which point the band will interrupt the beam of the electric eye 28, whereupon the solenoid 20 will be deactivated, the clutch 19 opened and the feed rolls 10, 11, stopped. As the machine is now set in operation, it will draw band from the magazine, and as soon as enough of the latter has been withdrawn to clear the beam of the electric eye, the feed rolls 10, 11, will be again actuated as hereinabove described, so that the band will be fed into the magazine by the said rolls as it is being withdrawn by the machine to be wound around a package. The arrangement is such that the machine draws the band from the magazine at the same rate or a little faster than it is fed into the magazine by the rolls 10, 11, but there is such an excess or surplus of band in the magazine that it is never all consumed in the binding of a package and there is seldom, if ever, less band in the magazine than the amount represented by the dotted line marked C. It will be understood that, at the completion of each banding operation, the feed rolls 10, 11, continue rotating until sufficient additional band has been fed into the magazine to reach the position marked D, or substantially that position, and interrupt the beam of the electric eye with the effect of deactivating solenoid 20 and stopping rolls 10, 11; at which moment also solenoid 9 is activated to brake reel 1 and prevent overfeeding or overthrow of the band from the reel. Thus it will be clear that the absence of the band from the end of the magazine at which the electric eye is located will start the feed rolls and release the reel and, vice versa, the presence of the band at that end of the magazine will stop the feed rolls and brake the reel. It should be added that, in place of the electric eye, a finger or light lever fitted to actuate a switch could be substituted for contact with the band, the arrangement being such that release of pressure by the band on the finger or lever will start the feed rolls and release the reel, while exertion of pressure on the finger or lever by the band will stop the feed rolls and brake the reel. This effect can be obtained by any appropriate combination of solenoids, springs, brakes and clutches, and calls for no further description in view of what has already been set forth. A stop E, consisting of a horizontally disposed rod, is positioned near the right hand end (Fig. 3) of magazine 24, which serves the purpose of preventing the loop of band from entering into and catching upon the edges of opening 25 with the possibility of resultant injury.

Turning now to Figs. 1, 4 and 6 through 9, the machine includes a main, substantially cubical, casing which is denoted generally by 30 and is preferably composed of steel or iron. The casing has front feet 31, 31, and rear feet of which one is shown and marked 32.

To the front of the casing 30 is secured an annular frame 33, also preferably composed of steel or iron, which has an integral web 34 extending downwardly

from the sides and bottom thereof, the lower edge of the said web being supported upon shoulders formed at the tops of feet 31, 31, as indicated at 35 in Fig. 4. The web is also fastened to the front of the casing 30 by bolts or the like (not shown) and is additionally secured in position by angle members which are bolted to the rear of the web at each side of the casing 30 and also to the casing itself, one of the said angle members being shown in Fig. 4 and marked 36; whereby the mounting of the annular frame 33 upon casing 30 is very rigid.

The frame 33 is substantially L-shape in cross section, as is well shown in Figs. 7, 8 and 9, with the longer dimension of its cross section extending in a radial direction, and the shorter dimension, corresponding to the foot of an L, extending axially toward the front of the machine and constituting a circular flange marked 37. The said flange is rabbeted to receive the outer circumference of an annular plate 38 which is fastened thereto by a series of screws, two of which are marked 39 in Fig. 1.

Interposed between frame 33 and plate 38 is a series of bearing rollers 40, each of which is mounted by ball bearings 41 on a screw stud 42 that is set in frame 33, a suitable number of the studs being fitted with eccentric sleeves 43 for adjustment purposes. The bearing rollers 40 are H-shape in cross section so as to adapt them to receive the inner circumferential toothed flange 44 of a ring gear 45, which is also formed with laterally projecting flanges 46, 46, that rest upon the peripheries of the rollers 40, whereby the ring gear may be rotated with the said rollers serving as its bearings.

The ring gear 45 carries a series of regularly spaced band receiving roll and guide units, each of which includes a roll 47, an inner guide 48, and an outer guide 49. The unit is fastened to the ring gear by a bolt 50 and is spaced therefrom by a collar 51. The roll 47 is mounted by ball bearings 52 on an enlargement 53 of the bolt, and the inner guide is positioned between the said bearing and the collar 51. Another spacing collar 54 is interposed between the said bearing and one of a pair of clamping nuts 55, 55, which grip the outer guide and secure the parts together. The inner faces of the guides are provided with wear plates 56, 56, preferably composed of hardened steel, which are fixed thereto by screws, and added rigidity is imparted to the unit by the fact that the collar 51 is jammed against a peripheral T-flange 57 formed on the outer circumference of the ring gear 45. These roll and guide units are preferably spaced so closely together that the band, when wrapped around them, takes a substantially circular rather than a polygonal form. A permanent keeper is provided to prevent the free end of the band from flapping when the machine is not being fed, and takes the form of an arcuate piece 58 (Figs. 1 and 9) which is positioned between the plates 56, 56, and has its ends fixed to flange 37 as shown at 58a, 58a.

The ring gear 45 also carries a pair of band tension roller 59, 60, each of which is mounted on a plain double bearing 61 (Fig. 6) that surrounds a T bolt 62, the head of which is received for slidable adjustment in an undercut groove formed in a block 63 which is fastened by a suitable number of screw bolts 64 to the ring gear. A nut 65 and washer 66 on each T bolt serve to fix its roller in place between a flange on the inner member of double bearing 61 and the washer.

Ring gear 45 is rotated by a main drive pinion 67 (Fig. 4) which is keyed or otherwise secured on a shaft 68 (see Figs. 18, 19 and 20) that is mounted by ball bearings 69, 70, and face plate 71 in a bearing box denoted generally by 72 which is supported within the casing 30 of the machine and receives a portion of the cam shaft 73 that carries the various activating cams and gears. The pinion 67 may be connected and disconnected with and from a spur gear 74, that is loosely mounted on shaft 68, by friction clutch mechanism 75 likewise

carried on said shaft; and the said gear 74 is in mesh with another gear 76, which is keyed or otherwise fixed to a worm shaft 77 which is mounted by ball bearings 78, 79, and thrust bearing 80 in the bearing box 72.

One end of shaft 77 projects outwardly from box 72 toward the rear in casing 30 and has suitably fixed thereto a belt pulley 81 which is connected by a belt 82 with the drive pulley 83 of an electric motor 84 that is fixed to the bottom of casing 30 by screw bolts two of which are shown and are marked 85, 85.

From the foregoing it will be seen that, when motor 84 is started and clutch 75 is closed, ring gear 45 will be rotated by pinion 67 which meshes with the teeth on the periphery of the ring gear, as is well shown in Fig. 4. The clutch 75 is operated by a bell crank lever which is fixed on a shaft 86 that is supported in the walls of bearing box 72 and has one arm 87 extending to the said clutch and another arm 88 (Fig. 17) secured to a pull chain 89 that passes over a sprocket 90 mounted at the top rear of box 72 and extends downwardly to a lug 91 (Fig. 16) which is pinned to a rod 92 that is slidably mounted in a sleeve 93 carried by an apertured plate 94 bolted to the rear wall of casing 30 in register with an opening 95 formed therein. The rod 92 also traverses a treadle 96 which is pivoted at 97 to a lug that is fixed to an edge of the base of motor 84; and an expansion spring 98 is confined between the underside of treadle 96 and a nut 99 which is threaded on the lower end of rod 92 to cushion the action of the treadle when it is depressed and to maintain the latter normally in a substantially horizontal position. An oil duct 100 serves to lubricate rod 92. Chain 89 is connected to lug 91 by a pin 101 that is slideable in the lug and has a pair of nuts 102 threaded on its lower end, so that downward motion of rod 92 will cause lug 91 to contact nuts 102 and impart similar motion to pin 101 with a pull upon chain 89. A collar 103 is pinned to rod 92 intermediate sleeve 93 and treadle 96 to limit the upward movement of the rod, and it will be understood that the connection of the rod to pull chain 89 normally restrains downward movement of the rod. An adjustable screw stop 104 that is threaded into the lower portion of plate 94 positively limits the downward travel of the treadle.

From the immediately foregoing description it will be clear that manual depression of treadle 96 will cause chain 89 to lift the outer end of arm 88 of the bell crank and cause the other arm 87 to close clutch 75 and fix gear 74 to shaft 68; whereas release of treadle 95 will allow but not cause opposite movement of the parts. The opposite movement is positively accomplished by a cam 105 that is fixed to rotate with shaft 73 and has a recess 106 in its periphery fitted to receive a roller 107 on the end of an arm 108 which is fixed to shaft 86. When arm 88 is lifted by chain 89 as above described to close friction clutch 75, roller 107 enters recess 106 but, as soon as shaft 73 starts to rotate, as will be hereinafter explained, cam 105 forces the roller out of the recess and opens clutch 75. Adjusting screws 109, 110, are provided for slightly varying the angularity of arm 108 with respect to shaft 86 to nicely control the closing and opening of the clutch.

A second pull chain 111 is also connected to rod 92 for actuation when treadle 96 is depressed, said chain passing around a sprocket 112, which is mounted along side of sprocket 90, and having its other end fastened at 113 to a projectable and retractable rod 114 which carries at its forward extremity a band guiding finger 115. The said rod is mounted in bearings 116, 117, formed on the top of box 72, bearing 117 having a slot 118 which slidably receives a pin 119 that extends laterally from the inner end of rod 114 to prevent rotary motion of the latter. An expansion spring 120 is compressed between bearing 117 and a collar 121 that is pinned to rod 114 for normally urging the rod to slide to the left in Figs. 18 and 19 and project its finger 115 into the path of the

band to be wrapped around a package, as will be hereinafter set forth. It will thus be clear that depression of treadle 96 to close clutch 73 will simultaneously cause chain 111 to retract rod 114 and its finger 115 for a reason to be later explained.

The machine includes means for automatically discontinuing the drive of the ring gear 45 when it has completed one revolution and simultaneously starting rotation of the cam shaft 73, which means comprises a dog 122 that is suitably fixed to the back of the ring gear by screws 123 or the like (see Fig. 5) and has a beveled nose 124 for cooperation with a beveled latch 125 which is slidably mounted in a block 126 that is secured by cap screws 127 to the annular frame 33. The rear end of latch 125 is connected at 128 to one arm 129 of a bell crank which is pivoted on a screw stud 130 that is set in frame 33 and has its other arm 131 connected to a chain 132 which passes around a sprocket 133 that has its hub mounted on a stud 134 which is set in a base 135 which is adjustably fixed by a screw and slot fastening 136, 137, to angle member 36 (see Fig. 4). An adjustable stop screw 138 serves to limit the movement of bell crank arm 129 under the pull of chain 132 to regulate the projection of latch 125 from its block 126. From sprocket 133 chain 132 leads through a hole 139 in the adjacent side of casing 30 to a sprocket 140 which is mounted on a screw stud 141 that is set in the upper part of bearing box 72 (see Fig. 18), and the chain is then fastened at 142 to the outer end of a trip latch 143 which is pivoted on a stud 144 that projects inwardly from a wall of box 72. The inner end of latch 143 is formed with a nose 145 fitted to cooperate with and normally urged by a spring 146 toward a shoulder 147 on the exterior of a single revolution clutch unit 148 that is mounted on and for driving engagement with the cam shaft 73, the adjacent end of which enters a cover plate 149 (see also Fig. 4) which is screw fastened to the outside of bearing box 72 and to which cover plate is screw fastened a cap 150 that conceals the end of shaft 73 and is provided with an oil gauge 151.

As the single revolution clutch unit is well known to mechanics in both structure and operation and can be obtained as a unit in the open market, it is deemed to call for no further description; but it should be pointed out that the driving means for cam shaft 73 consists of a worm 152 fixed on shaft 77, and a cooperating worm gear 153 which is loosely mounted on shaft 73 but fitted to be brought into driving relationship therewith by the single revolution clutch 148.

It will be seen from the foregoing description that manual depression of treadle 96 will cause ring gear 45 to rotate and that, when the ring gear has completed one revolution, the contact of its dog 124 with latch 125 will trip clutch latch 143 and permit single revolution clutch 148 to cause rotation of cam shaft 73 which will be arrested at the end of one revolution by engagement of latch 143 with shoulder 147 under the influence of spring 146. Further, at the instant cam shaft 73 begins to rotate, cam 105 will cause arm 106 to swing bell crank arm 87 and open friction clutch 75, whereupon the rotation of ring gear 45 will cease. The depression of treadle 96 also momentarily withdraws rod 114 which carries finger 115 so that the latter will not interfere with the initiation of the step of wrapping the band around a package.

There is provided gripping mechanism for seizing the end of the incoming band, feeding it forwardly, and tensioning the band after it has been wrapped around a package. In each cycle of operation of the machine, i. e., in the banding or strapping of each package, the gripping element of this mechanism seizes and holds the band, moves forwardly along the line of band feed to tension the band around the package, opens slightly to release the band, moves laterally away from the line of

band feed, fully opens, moves rearwardly along a line parallel to the line of band feed, moves laterally toward and to the line of band feed and closes for seizing the end of the next band, moves forwardly slightly along the line of band feed to advance the free end of the band over the overlap of the previous band, and then moves further forward to feed band material into position for the overlap of the next band. This mechanism will now be described with particular reference to Figs. 37-43 and 23-26.

A head piece 154 is fixed, as by set screws 155, 155, on a slide guide shaft 156 one end of which is supported in a bearing 157 carried by framework 158 positioned within the casing 30, while the other end is supported in a bearing 159 that is also carried by the framework. Rocking of the head on shaft 156 is prevented by a steady rod 160 which traverses the head at 161, is mounted in the said framework at 162, 163, and is fixed against movement by a set screw 164. The head piece is also traversed by an operating shaft 165 one end of which is mounted for restricted sliding movement in the head piece at 166, while the other end is slidably received in a bearing 167 formed in an upper corner of the framework 158 (Fig. 23). The end of shaft 165 within head piece 154 is reduced in diameter to form a shoulder 168 (Fig. 38) which abuts a cooperating shoulder 169 formed in the head piece so that movement of the shaft to the right in Fig. 37 will impart corresponding motion to the head piece; and the extremity of the said end of the shaft is surrounded by an expansion coil spring 170 which is held against head piece 154 by adjustable nuts 171, 171, that are threaded on the shaft, so that movement of said shaft 165 to the left in Fig. 37 will impart corresponding, but yielding, motion to the head piece in order to tension the band with yielding, variable force.

Movement of shaft 165 is controlled by a drum cam 172 that is fixed on cam shaft 73 at the side of the machine which is distant from bearing box 72, the said portion of shaft 73 having a combined ball and thrust bearing 173, 173a in one end of framework 158 and a ball bearing 174 in a partition 175 therewithin. It should here be noted that the cam shaft 73 is in two parts which are united by a coupling 176 (Fig. 21) in order to insure proper operation even under conditions of slight misalignment and to facilitate assembly of the machine. Cam 172 has a groove 177 formed in its periphery which is fitted to receive a roller 178 that is carried on one branch 179 of a bent arm which is pivoted at 180 on a mounting 181 fastened by cap screws 182 to the bottom of framework 158. The other branch 183 of the arm extends upwardly and is bifurcated, the bifurcations being provided with slightly elongated apertures 184, 185, to receive the ends of a pin 186 which is set in a flattened portion 187 of shaft 165. As a result of this arrangement, rotation of cam 172 will slide shaft 165 to the right and left in alternation by swinging the bent arm on its pivot 180, and the elongation of apertures 184, 185, will prevent cramping of the parts. This causes the head piece 154 to move forward and backward along the line of band feed, and the forward movement is capable of yielding by compression of spring 170 so that the force of this movement, which serves to tension the band around the package, can be varied by adjusting the nuts 171, 171, on shaft 165, thereby serving to vary the tension of the band on the package. These forward and backward movements of the head piece are step-by-step as is indicated by the layout of cam groove 177 in Fig. 26, and meet additional purposes, as will be later explained.

The head piece 154 is formed with a pair of side walls 188, 189 (Fig. 37), at its top to provide a channel 190 for receiving the band feeding and tensioning gripper and its actuating mechanism and permitting the same to be moved laterally away from and back to the line of band feed. The said band feeding and tensioning

gripper consists of a fixed jaw 191 and a complementary movable jaw 192 which latter is connected with the former by a pivot 193, both said jaws being adjustably mounted on a sliding block 194 positioned within said channel and limited in its sliding movement by a stud 195 which projects laterally from both sides thereof and rides in slots 196, 196, formed in walls 188, 189. The lower part of block 194 is bifurcated to receive a slide 197 to the forward end of which is pivoted a triangular link 198 that is connected by another link 199 with movable jaw 192 and is also pivoted to sliding block 194. Thus, motion of slide 197 in block 194 will open and close movable jaw 192, while movement of block 194 in head piece 154 will carry both jaws 191, 192, into and away from the line of band feed. When block 194 is in line of band feed, its movement to the right away therefrom is prevented by a spring pressed catch 200 until the catch is released as hereinafter described, and the extent of movement of block 194 away from the line of band feed is limited by the length of slots 196, 196.

A spring pressed ball plunger 201 is mounted vertically in block 194 and its ball cooperates with two depressions 202 and 203 formed in the top of slide 197, depression 202 being of a size snugly to receive the ball while depression 203 is elongated in the direction of movement of block 194. It will thus be seen that, with the parts in the positions shown in Fig. 40, a slight movement away from the line of band feed (to the right) of slide 197 while block 194 is held by catch 200 will move the ball of plunger 201 from the rear end of depression 203 to its front end and will simultaneously cause linkage 198, 199, to slightly open jaw 192 for releasing its grip upon the band. If not, catch 200 releases block 194, continued movement to the right of slide 197 will carry block 194 along with it because of the position of the plunger ball in depression 203. This movement will shift the jaws 191, 192, bodily to the right and will continue until stud 195 hits the rear end of slots 196, 196, and halts the movement of block 194. Continuation of this movement by slide 197 will develop relative motion between it and the block to cause linkage 198, 199, fully to open jaw 192 while the ball of plunger 201 travels from depression 203 to depression 202 and enters the latter to lock the jaw in open position as shown in Fig. 41. Reverse to the left movement of the parts has effects opposite to those just described and returns the parts to the positions shown in Fig. 40. In order to insure accuracy in the movement of slide 197 in block 194, the former is provided with tongues 204, 205 (Fig. 43), on its opposite sides which travel in grooves formed in the inner faces of the bifurcated portion of block 194.

Adjustability of jaws 191, 192, in block 194 is obtained by a screw and slot fastening 191a, 191a (Fig. 38), and such adjustment to the right or left correspondingly moves pivot 193 which will cause linkage 198, 199, to close jaw 192 with varying degrees of tightness.

The movements of slide 197 are generated and controlled by a closed cam 206 which is keyed to cam shaft 73 and receives in its groove 207 the roller 208 of a rock lever that is composed of two members 209, 210, which are pivoted on a shaft 211 that is mounted at both ends in framework 158. The upper ends of members 209, 210, are united by a shaft 212 and are capped by a cross head 213 in which is formed a channel 214 that receives a roller 215 which is fixed to slide 197 by a screw 216. The lower parts of members 209, 210, are also connected by a rod and spring assembly that will be described later as it does not affect the functioning of the parts not being explained. To one end of cross head 213 is fastened a plate 217 formed with a cam slot 218 in which rides a stud 219 carried by an arm 220 that is fixed to catch 200. As cam 206 rotates, lever 209, 210, will move slide 197 and its associated parts toward and away from the line of band feed (i. e., to the left and right) while the cam slot 218 will lift catch 200 against the pressure of its spring and permit return motion thereof so as to release

and restrain block 194 at the proper times in the cycle of operation of these parts hereinabove described. The purpose of catch 200 is to insure a slight relative movement of slide 197 with respect to block 194 and thus cause a slight opening of jaw 192 so as to release the band before any bodily movement of the gripper 191, 192, away from the line of band feed occurs. The channel 214 is provided in cross head 213 to permit roller 215 to travel with the head piece 154 and parts carried thereby as the latter is reciprocated by slide shaft 165 as previously explained.

Thus the mechanism in the functioning of this feeding and tensioning gripper enables it to seize and hold an incoming band, tension it after it has been wrapped around a package and clamped by a holding gripper (to be described), open slightly to release it after it has been also clamped by an auxiliary holding gripper (likewise to be described), move away from the line of band feed, move backward parallel with said line of feed toward the source of band supply, open fully, and then return to the said line and close to seize the succeeding band, feed it forward slightly to advance its free end over the overlap of the previous band, feed it further forward into position for the overlap of the next band, and hold it for repetition of the cycle of steps just recited.

Turning now to the band holding gripper, attention is directed particularly to Figs. 21, 30, 31 and 32, from which it will be seen that the gripper has an upper fixed serrated jaw 221 which is screw fastened to the under side of the front edge of the top 222 of casing 30, and a lower serrated jaw 223 that is pivoted at 224 in a cleat 225 which is secured by screws to the under side of top 222 adjacent the upper jaw. The lower jaw is also pivoted to the head 226 of a screw threaded actuating rod 227 which has its other end supported by an arm 228 that is centrally pivoted for rocking motion on a pin 229 which is mounted in framework partition 175. The other end of arm 228 carries a roller 230 which runs on the periphery of a cam 231 that is keyed on the cam shaft 73, which latter, at this point, is supported in a bearing 232 on partition 175. Roller 230 is held in contact with cam 231 by sprocket chain 233 which is fastened at 234 to arm 228 and at 235 to a retractile spring 236 that is adjustably secured to a clip 237 fixed on framework 158. A sprocket 238 is carried in a bearing 239 which is screwed to the upper rear edge of the framework and serves to support the chain. The upper end of arm 223 is bifurcated and receives suitably fixed pivot pins 240, 240, which enter opposite sides of a block 241 that is slidably mounted on rod 227. A collar 242 is fitted on the said rod and adjustably held against movement to the right in Figs. 30-32 by nuts 243, 243, that are threaded on the rod. The adjustment of these nuts will vary the effective length of rod 227. Block 241 carries a similar collar 244 which serves as an abutment for one end of an expansion spring 245 which surrounds the rod and the other end of which abuts a collar 246 which is adjustably held against movement to the left in Figs. 30-32 by nuts 247, 247, threaded on the rod, for varying the compression of the spring. Spring 236, acting through chain 233, not only holds roller 230 against cam 231 but also causes arm 228 to pull backwardly on rod 227 and tend to hold jaw 223 in open position. Movement of the said jaw to closed position is caused by cam 231 when roller 230 rides on the high or long radius edge portion of the cam. It will thus be evident that rotation of cam shaft 73 as heretofore described will alternately close and open the band holding gripper jaw 223, the latter being held closed as long as roller 230 is riding on the high portion of the cam during which period the band is being tensioned around the package by the feeding and tensioning gripper 191, 192, as previously explained. When roller 230 is riding the low portion of the cam the jaw 223 is opened to release a finished band and to be ready to grip a succeeding band after it has been wrapped around a package. The

adjustability of the length of rod 227 and of the strength of springs 245 and 236 provides for regulating the action of jaw 223 including the force with which it grips the band under the cushioning effect of spring 245.

The machine also embodies an auxiliary band holding gripper which serves the purpose of holding the underlapped portion of the band in tensioned condition while the overlapped portion is being severed from the band supply and the said portions are being welded together. This gripper also acts to bend the band to cover the free end thereof, cooperates with the cutter for severing the band, and forms the female half of means for crimping the end of a succeeding band, as will be hereafter described. This auxiliary gripper is positioned between the feeding and tensioning gripper 191, 192, and the holding gripper 221, 223, in the line of band feed.

Referring particularly to Figs. 33-36, the said gripper has a fixed serrated upper jaw 248 which is screw fastened to the under front edge of casing top 222, and a lower movable serrated jaw 249 that is pivoted at 250 in a cleat 251 which is secured by screws to the under side of top 222. Jaw 249 is connected by a pivot 252 with an actuating rod that may be, for a purpose to be described, composed of two members 253, 254, which are pivotally jointed at 255. The rear end of member 254 is adjustably connected by a screw coupling 256 to a link 257 that is pivoted at 258 to an arm 259 which is mounted at 260 in an inward projection of framework 158 for rocking motion and carries on its lower end a roller 261 which travels in the groove 262 of a closed cam 263 that is fast on cam shaft 73.

A cutter 264 associated with this auxiliary gripper is also pivoted at 250 in cleat 251 and is connected by pivot 252 with an actuating rod 265 that is adjustably connected by a screw coupling 266 with a link 267 which is pivoted at 268 in the upper end of an arm 269 that is mounted for rocking motion at 270 in the said inward projection of framework 158. The lower end of arm 269 is fitted with a roller 271 which rides on the periphery of a cam 272 that is fixed to the cam shaft 73. A sprocket chain 273 is fastened at 274 to the upper part of arm 269 and at 275 to the upper end of a retractile spring 276 which has its lower end secured to a clip 277 that is fixed to framework 158. A sprocket 278 mounted in a bearing 279 on the upper rear edge of the framework supports the chain 273, and it will be seen that the effect of these parts is to hold roller 271 against cam 272. Groove 262 of cam 263 and the periphery of cam 272 are of such shape and the cams are so positioned on shaft 73 that rotation of the latter causes the band to be gripped and held by the jaws 248, 249, while the tensioning gripper 191, 192, releases the band and the latter is severed by cutter 264 which cooperates with the lower part of jaw 249, as well shown in Figs. 10-12.

The cutter mechanism also serves to crimp the end of the succeeding band to prevent it from catching on the plate which cooperates with the welding electrodes (to be hereafter described) or on the overlap of the preceding band. This is accomplished by a male die 280 (Figs. 10-12) that is carried by cutter 264 and mates with an inverted V-shaped groove 281 formed in the bottom of jaw 249.

As this auxiliary band holding gripper may in some cases be subjected to considerable strain due to the tension of the band, there may, if desired, be associated with the mechanism which actuates jaw 249 means for increasing the power with which it acts. The said means includes a plunger 282 which is slidably mounted in a block 283 fixed at the front of framework 158. The top of the plunger abuts a roll 284 which is eccentrically mounted in the pivotal joint 255 that connects members 253 and 254, while the lower portion of the plunger is provided with a collar 285 that is adjustably pinned thereto and serves to confine an expansion spring 286 between itself and the bottom of block 283. The lower

extremity of plunger 282 traverses the front end of an arm 287 and is adjustably secured thereto by nuts 288, 289, which are threaded on the plunger. Arm 287 is pivoted at 289 for rocking motion in a support 290 that

5 uprises from the bottom of framework 158, and the rear end of the said arm carries a roller 291 which rides on the periphery of a cam 292 that is fixed on shaft 73, the roller being held against the cam by the effect of spring 286. It will thus be seen that rotation of shaft

10 73 will force plunger 282 upwardly when roller 291 is on the high or long radius portion of cam 292 and this movement of the plunger will straighten members 253, 254, with a toggle action and force movable jaw 249 with added power toward fixed jaw 248 so as more firmly

15 to grip the band therebetween. This action is cushioned by an expansion spring 293 which is positioned between the tail end of member 253 and member 254, the said tail end being loosely pinned to member 254 at 294.

20 We have found that there is usually no need for providing the machine with the just described means for increasing the power with which this auxiliary band holding gripper acts, and, with a view to avoiding unnecessary complication, prefer to omit the said means

25 entirely and to substitute for the jointed actuating rod 253, 254, 255, a simple spring loaded rod such as is shown in Fig. 34a. This rod is marked 254a and has one end threaded into the link 257 while the other end has a pin and slot engagement 254b with and slides in a

30 bored head 254c that is connected with pivot 252. An expansion spring 254d surrounds rod 254a and is confined between head 254c and an adjustable collar 254e to cushion the effect of rod 254a when actuated by arm 259. A nut 254f is provided for adjusting rod 254a in link 257.

35 It may be added that it is desirable to so form the contacting surfaces of jaws 248 and 249, as indicated at 295 (Figs. 10-12) that their closing will slightly bend the band at the overlap, as illustrated at 296 in Fig. 40 13, to snugly receive the cut off end.

40 After the band has been severed and while it is still held by gripper jaws 221, 223, and 248, 249, the overlapped portions thereof are welded together. The means for accomplishing this is shown in Figs. 21, 22, 27, 28,

45 29, and includes a pair of electrodes 297, 298, which are carried at the front ends of the transformer buss bars 299, 300, that have their rear ends provided with plate contacts 301, 302, which are fastened by screws 303 to the laminated U-shaped resilient metallic outlet

50 304 of a transformer unit only part of which is shown and marked 305 as such unit suitable for this machine are obtainable on the open market. The said electrodes and buss bars are separated by suitable insulation that is fitted in the space 306 therebetween.

55 In operation, the buss bars are moved forward, which motion is permitted by the resiliency of outlet 304, and their front ends carrying the electrodes are moved upward to perform the welding step, following which the said motions are reversed to complete the cycle. The mechanism for imparting these motions comprises a closed cam 307 which is fixed to shaft 73 and has a

60 groove 308 that receives a roller 309 carried in the end of an arm 310 which is fast to a shaft 311 mounted in the lower part of framework 158. A pair of longer arms 312, 313, are also fixed to shaft 311 and extend upwardly at each side of buss bars 299, 300, to which they are secured by a suitably insulated pin 314 which traverses the said bars. The arms 312, 313, are interconnected by reinforcing webs 315, 316. Thus rotation

65 of the cam shaft 73 will cause cam 307 to rock arms 312, 313, and move buss bars 299, 300, forward and backward. Upward movement of the front ends of the bars which carry electrodes 297, 298, is effected by means 70 including a cam 317, which is also fixed to shaft 73, on 75

the periphery of which rides a roller 318 that is mounted in the bifurcated upper end of one branch 319 of an angle arm which is journaled on a shaft 320 mounted in the lower part of framework 158. The other branch 321 of said angle arm is also bifurcated and is connected by pivots 322, 323, with a pair of links 324, 325, that are pivoted to and extend upwardly from trunnions 326, 326, which are integral with a cross head 327. A pair of plungers 328, 328, are slidably mounted in a bracket 329 that is fixed by screws 330 to the inside of the front of framework 158, and their lower ends pierce cross head 327. Said lower ends of the plungers are surrounded by like sleeves 331, 331, which are fixed to cross head 327 by a plug set screw 332 and serve to back collars 333, 333, against which abut the lower ends of like expansion springs 334, 334, while the upper ends of said springs abut similar collars 335, 335, that are backed by enlarged portions near the upper ends of said plungers but below bracket 329. Adjustable collars 336, 336, on the plungers serve to regulate the tension of the springs.

From the immediately foregoing description it will be evident that rotation of shaft 73 will cause cam 317 to lift plungers 328, 328, in bracket 329 and that the force exerted will be cushioned by springs 334, 334. Each plunger is provided at its top with like means for elevating the bars 299, 300, one of which is shown and will be described. Said means consists of a collar 337 which is pinned or otherwise secured to the plunger and carries a lower shoe 338 and an upper shoe 339, between which is a layer of insulation 340, said elements being held together by insulated screws 341. A contact piece 342 is set in the under side of each buss bar to receive the push of upper shoe 339 and the surface of said piece is convex to accommodate the upward movement of the buss bar under the impulse of the plunger. A short circuiting plate 343 is fixed to the under side of the front edge of the top 222 of casing 30 for cooperation with the electrodes 297, 298, in the band welding operation.

Means is also provided for preventing undesirable shock or jar in the operation of these parts, which means comprises an arm 344 that has one end mounted on shaft 320 and the other end fitted with a roller 345 that rides on the periphery of a cam 346 which is also fixed to cam shaft 73. Arm 344 is fastened to angle arm 319, 321, by pins 347 so as to move therewith, and it will be observed that cams 317, 346, are so shaped and so positioned with respect to each other that, in their action upon rollers 318 and 345, the one, in effect, counterbalances the other to an extent sufficient to obtain smooth action of the parts activated thereby. This result is insured by an expansion spring 348 which is connected to the under side of branch 321 of the angle arm by a pilot pin 349 and is adjustably confined at its lower end by a screw plug 350 which is threaded in a sling 351 that depends from framework 158 whereby said spring cushions, with variable strength, the downward motion of said branch 321 of the angle arm.

The initiation and duration of the welding period is regulated by a micro switch unit 352 in the electric circuit which is screw fastened to framework 158 and provided with a spring biased arm 353 that holds a roller 354 against a cam which is composed of two parts 355, 356, that are relatively adjustable in the usual way to afford a longer or shorter high or long radius edge portion for cooperation with the roller. The said cam 355, 356, is fixed on cam shaft 73 and is therefore rotated in unison and in proper timed relation with the cams that operate the electrodes. This control arrangement may be supplemented by additional devices as will be later explained in connection with description of the general wiring layout of the machine.

The machine also includes manually operable means for momentarily opening jaw 192 of the feeding and tensioning gripper in order to insert the end of the band when

beginning the use of a spool or reel, which means (see Figs. 37, 39, 42 and 43) consists of a handle 357 that is provided with a cam head 358 and is pivoted at 359 to a rod 360, which rod connects the lower parts of members 5 209, 210, is fixed in position by a pin 361, and is surrounded by an expansion spring 362. When handle 357 is pulled to the left (Fig. 39) cam 358 turns on pivot 359 and pulls rod 360 and member 210 against the action of spring 362. This swings member 210 on shaft 212 and causes cross head 213, through roller 215, to move slide 197 relatively to block 194 and thereby slightly to open jaw 192.

A back stop 363 (see Figs. 1, 4, 10, 11, 12) is adjustably secured, as by one or more clamps 364 of any approved kind, to the casing top, against which the packages to be strapped are placed, and it will be noted that the position of the back stop is such that the winding of the band around the package in an anti-clockwise direction tends to force the package against the stop. As shown, the stop is near the limit of its adjustment to the right. Movement of the packages on the casing top is facilitated by a layer of balls 365 in sockets 366 (see Fig. 4), and the packages may be taken from the machine manually or automatically by a series of rollers 367 mounted in a frame 368 adjacent the machine. A guide 369 on the casing top prevents packages leaving the back stop from getting out of line and another guide 370 on frame 368 assists in directing the strapped packages to rollers 367. The last named guide may be supplemented by a similar guide (not shown) positioned at the opposite ends of the rollers and the said two guides may be set at an angle to each other in order to, so to speak, funnel the packages onto the rollers. A traveling belt (not shown) may be substituted for the rollers if desired. A pair of band guides 371, 372, are also positioned at the front edge of the casing top to restrain the band against lateral movement, and these guides are preferably supplemented by complementary guides (not shown) fixed on the frame 368 in position to contact the adjacent edge of the band.

40 As indicated above, additional means for control of the welding step may be provided, and such means is shown in Fig. 53 in connection with the general wiring diagram or layout of the machine. In this figure the micro limit switch 352 is arranged in circuit with an electronic timer 373 provided with a safety switch 374 which need not be described since it is available as a unit in the open market. This timer is, in turn, electrically connected with a contactor 375, one side of which is connected through an eight step regulator 376 with the transformer 305 that feeds the welding electrodes 297, 298. The other side of the contactor and the regulator are connected with a welding switch 377 which is also connected with timer 373, as shown in Fig. 53. The said welding switch is wired to motor switch 378 which, 45 through an automatic starter 379 that has a control station 380 and a microswitch 381, is connected to the main machine drive motor 84. Switch 378 is also in connection with a manual starter 382 that is wired to motor 18 that drives the band feed rolls 10, 11, as well as, 50 through microswitch 383, to solenoids 9 and 20. Current is supplied from any suitable source through line wires 384. It will be observed that, in this arrangement, the microswitch 383 replaces the electric eye unit 28 as suggested in an earlier part of this specification. In view of the fact that the elements composing this control system, and the functioning thereof, are well known to operatives skilled in this field, it is deemed unnecessary here to enter into further description.

55 The operation of each of the functioning parts of the machine has been set forth in connection with the description of the mechanism, but it may be helpful here briefly to summarize the operation of the machine as a whole in strapping an article.

In preparing to start operation the band is led manually from the supply reel 1, threaded underneath roll 22,

between feed rolls 10, 11, and looped in the magazine 24 to approximately the extent indicated by C in Fig. 1. The end of the band is then passed around guide rolls 26, 27, tension rolls 59, 60, under finger 115, and into jaws 191, 192, of the feeding and tensioning gripper, which are momentarily opened by actuation of handle 357. The electric current for the machine is now turned on which starts motor 18 and brings feed rolls 10, 11, into action with the result that band accumulates in the magazine 24 until it reaches approximately the position denoted by D in Fig. 1, at which moment the interruption of the electric eye beam (or similarly functioning alternative device hereinabove mentioned) by the band stops the feed rolls. The operator now depresses pedal 96 which closes clutch 75 and starts ring gear 45 in rotation by motor 84, also simultaneously temporarily retracting finger 115 so that it will not interfere with the band as the ring gear wraps it around the article being strapped. When the wrapping is completed by one revolution of the ring gear, the drive of the latter is automatically disconnected by contact of dog 122, 124, with latch 125 which activates the one revolution clutch that drives cam shaft 73, the initiation of the rotation of the cam shaft serving positively to open clutch 75 and permit ring gear 45 to halt. The continued rotation of cam shaft 73 causes its cam 231 to close the jaws 221, 223, of the holding gripper upon that portion of the wrapped band lying at the side of the welding electrodes that is away from the feeding and tensioning gripper. Immediately thereafter the drum cam 172 moves the feeding and tensioning gripper 191, 192, with the end of the band it is gripping, toward the holding gripper 221, 223, to tension the band around the article. The auxiliary band holding gripper 248, 249, is now closed by cam 263 upon the end of the band at a point adjacent the side of the electrodes that is opposite holding gripper 221, 223; whereupon the feeding and tensioning gripper 191, 192, is slightly opened by its operating mechanism to release the band and start on its withdrawal movement which carries it laterally away from the line of band feed, then rearwardly toward the source of band supply in substantial parallelism with said line, then laterally toward and to said line, at which moment the jaws 191, 192, which have been fully opened, close upon a succeeding portion of the band that will become the free end of the next band. During the just described movements of the feeding and tensioning gripper the electrodes have begun to move toward the line of band feed under the influence of cam 307 on shaft 73 and, with the parts in the last named position, cutter 264 is activated by cam 272 to sever the band and crimp the end of the succeeding band, which action is immediately followed by upward movement of the electrodes 297, 298, under the influence of cam 317 on shaft 73 which presses the overlapped portions of the band against plate 343 to weld them together, the duration of the welding period being controlled by microswitch unit 352 and the control system above described. The electrodes are then lowered from the band and withdrawn to their inoperative position, the cutter is likewise withdrawn to its inoperative position and the holding jaw and auxiliary holding jaw are opened so that the completely strapped article may be removed from the machine or advanced for the purpose of having another band applied thereto. Just prior to the full opening of the auxiliary holding jaw, the feeding and tensioning gripper makes its slight forward movement to cause the end of the band it is holding to pass over the previously formed band overlap, and the auxiliary holding jaw fully opens to permit the said end of the band to snap up against the previously formed band overlap. The auxiliary holding gripper then partially closes to permit the succeeding wrapping step to place the band against the lower side thereof in severing and crimping position and the feeding and tensioning gripper makes its forward movement to bring the end of

the band it is holding into overlapping position. The single revolution clutch unit 148 which serves to drive cam shaft 73 is now released, the motion of the cam shaft is arrested at the end of one revolution by engagement of latch 143 with shoulder 147 as heretofore described, and the machine is in condition for repetition of its cycle of operations in applying, tensioning, severing and welding a succeeding band. In this connection, it should be noted that the machine withdraws band from the magazine 24 at the same rate or a little faster than it is fed thereinto by rolls 10, 11, but there is always a sufficient amount of band in the magazine so that under no circumstances is it all consumed in the wrapping or binding of an article and, indeed, there is usually an amount of band in the machine as represented by the dotted line marked C in Fig. 1, except in the case of packages of large size. Furthermore, at the end of each banding or strapping operation, rolls 10, 11, continue feeding band into the magazine until it reaches substantially the position marked D in Fig. 1, whereupon it interrupts the beam of the electric eye 28 (or alternative device) which deactivates solenoid 20 and activates solenoid 9 to stop rolls 10, 11, and brake reel 1 to prevent overfeeding of band from the reel. It has been pointed out that, following the complete application of a band to an article, the movable jaw 223 of the holding gripper, the welding electrodes, and the cutter are withdrawn from the line or plane of band application so as not to interfere with the wrapping of a succeeding band, but mention should be made in this regard of the fact that movable jaw 249 of the auxiliary gripper is so timed in its operation as to partly close promptly following the welding step so that the succeeding band will be wrapped under the said jaw, as clearly shown in Figs. 10 and 11, in order to be in position to be severed and crimped by the cutter 264. The ring gear 45 will usually come to a stop at the end of one revolution, as above described, without the provision of any means for arresting it but, if particular conditions should make it desirable, any appropriate form of braking mechanism may be included for insuring its stoppage at the end of each driven revolution. It may also be noted that the manner in which the band is threaded around tension roll 59, as shown in Fig. 10, insures a slight curl or bend in the band so that its end under the package takes substantially the bowed form shown in the said figure.

While the description of the various parts of the machine and the operation of the machine have been directed to the wrapping of articles with band withdrawn from a source of supply such as a reel, it should be observed that, as in the case of the apparatus shown in the patent and application hereinabove named, the wrapping operation causes band to accumulate on the annular series of band receiving units carried by ring gear 45 so that, after a supply reel of band has been exhausted, the machine continues in operation by withdrawing band from the said accumulation on ring gear 45, and a new reel of band is not required until the said accumulation of band has been consumed. As this wrapping procedure by withdrawal of band accumulated on the ring gear has been fully set forth in the above named patent and application and as it per se forms no part of the present invention, there is deemed to be no occasion further to show or describe the same herein, but it should be mentioned that accumulation of band on the band receiving units carried by the ring gear should be controlled by suitable means such, for instance, as the means disclosed in the co-pending application of John James Cheesman, Serial Number 604,882, filed July 13, 1945.

It will be understood that various changes may be resorted to in the form, construction, material and arrangement of the parts without departing from the spirit or scope of the invention, and hence we do not intend to be limited to details herein shown or described except

as they may be included in the claims or be required by disclosures of the prior art.

What we claim is:

1. A machine of the character described comprising; means for wrapping band around an article, and means for tensioning the band after wrapping, said tensioning means including, a gripper for seizing the band, and mechanism for opening and closing the gripper and moving it bodily in a substantially rectangular path, said mechanism embodying at least one pivoted jaw, a plurality of slides operatively connected with the gripper, and means for causing both relative and combined movement of the slides.

2. A machine of the character described comprising, means for wrapping band around an article, and means for tensioning the band after wrapping, said tensioning means including, a gripper for seizing the band, and mechanism for opening and closing the gripper and moving it bodily in a substantially rectangular path, said mechanism embodying at least one pivoted jaw, a plurality of slides operatively connected with the gripper, and means for first causing relative movement, then combined movement, and then relative movement of the slides.

3. A machine of the character described comprising, means for wrapping band around an article, and means for tensioning the band after wrapping, said tensioning means including, a gripper for seizing the band, and mechanism for opening and closing the gripper and moving it bodily in a substantially rectangular path, said mechanism embodying at least one pivoted jaw, a plurality of slides operatively connected with the gripper, means for causing both relative and combined movement of the slides, and linkage connecting at least one of the slides with the pivoted jaw.

4. A machine of the character described comprising, means for wrapping band around an article, and means for tensioning the band after wrapping, said tensioning means including, a gripper for seizing the band, and mechanism for opening and closing the gripper and moving it bodily in a substantially rectangular path, said mechanism embodying a head piece, a pair of jaws mounted therein, at least one of the jaws being pivoted, means for reciprocating the head piece substantially in line with the line of band feed, a plurality of slides carried in the head piece, linkage connecting the slides with the pivoted jaw, means for causing relative movement of the slides, and means for reciprocating the combined slides substantially at right angles to the line of band feed.

5. A machine of the character described comprising, means for wrapping band around an article, and means for tensioning the band after wrapping, said tensioning means including, a gripper for seizing the band, and mechanism for opening and closing the gripper and moving it bodily in a substantially rectangular path, said mechanism embodying a head piece, a pair of jaws mounted therein, at least one of the jaws being pivoted, means for reciprocating the head piece substantially in line with the line of band feed, a plurality of slides carried in the head piece, linkage connecting the slides with the pivoted jaw, means for causing relative movement of the slides, means for reciprocating the combined slides substantially at right angles to the line of band feed, said means for causing relative movement of the slides including a yielding interconnection and a device for temporarily restraining movement of one of the slides.

6. A machine of the character described comprising, means for wrapping band around an article, and means for tensioning the band after wrapping, said means including, a gripper for seizing the band, and mechanism for opening and closing the gripper and moving it bodily in a substantially rectangular path, said mechanism embodying a head piece, a pair of jaws mounted therein, at least one of the jaws being pivoted, means for recip-

rocating the head piece substantially in line with the line of band feed, a plurality of slides carried in the head piece, linkage connecting the slides with the pivoted jaw, means for causing relative movement of the slides, and means for reciprocating the combined slides substantially at right angles to the line of band feed, said means for causing relative movement of the slides including a yielding interconnection and a device for temporarily restraining movement of one of the slides, and said yielding interconnection having complementary spring biased plunger and recess elements.

7. A machine of the character described comprising, means for wrapping band around an article, and means for tensioning the band after wrapping, said tensioning means including, a gripper for seizing the band, and mechanism for opening and closing the gripper and moving it bodily in a substantially rectangular path, said mechanism embodying a head piece, a pair of jaws mounted therein, at least one of the jaws being pivoted, means for reciprocating the head piece substantially in line with the line of band feed, a plurality of slides carried in the head piece, linkage connecting the slides with the pivoted jaw, means for causing relative movement of the slides, and means for reciprocating the combined slides substantially at right angles to the line of band feed, said means for causing relative movement of the slides including a yielding interconnection and a device for temporarily restraining movement of one of the slides, and said yielding interconnection having complementary spring biased plunger and recess elements, and said means for reciprocating the combined slides being provided with an element for releasing the said device for temporarily restraining movement of one of the slides.

8. A machine of the character described comprising, means for wrapping band around an article, means for tensioning the band after wrapping, means for holding the band against the pull of the tensioning means, means for releasing the tensioning means from the band, and auxiliary means for holding the band under tension when the tensioning means is released, said auxiliary holding means including gripping jaws, means for opening and closing the jaws, and toggle mechanism for increasing the power of the closing movement.

9. A machine of the character described comprising, means for wrapping band around an article, means for tensioning the band after wrapping, means for holding the band against the pull of the tensioning means, means for releasing the tensioning means from the band, and auxiliary means for holding the band under tension when the tensioning means is released, said auxiliary holding means including gripping jaws, means for opening and closing the jaws, and yielding toggle mechanism for increasing the power of the closing movement.

10. A machine of the character described comprising, means for wrapping band around an article, means for tensioning the band after wrapping, means for holding the band against the pull of the tensioning means, means for releasing the tensioning means from the band, and auxiliary means for holding the band under tension when the tensioning means is released, said auxiliary holding means including gripping jaws, positively acting means for opening and closing the jaws, and yielding toggle mechanism for increasing the power of the closing movement.

11. A machine of the character described comprising, means for wrapping band around an article, means for tensioning the band after wrapping, means for holding the band against the pull of the tensioning means, means for releasing the tensioning means from the band, and auxiliary means for holding the band under tension when the tensioning means is released, said auxiliary holding means including gripping jaws, positively acting means for opening and closing the jaws, and yielding toggle mechanism for increasing the power of the closing move-

ment, said toggle mechanism including jointed members connecting a jaw with the opening and closing means, a plunger disposed in operative relationship with the joint of said members, and cam actuated means for urging the plunger against the joint.

12. A machine of the character described comprising, means for wrapping band around an article, means for tensioning the band after wrapping, means for holding the band against the pull of the tensioning means, means for releasing the tensioning means from the band, and auxiliary means for holding the band under tension when the tensioning means is released, said auxiliary holding means including gripping jaws, and means for opening and closing the jaws, one of said jaws being so formed as slightly to bend the end of the band away from the plane of the adjacent portion when it is gripped and thereby provide for snugly receiving the overlapped end of a tensioned band.

13. A machine of the character described comprising, means for wrapping band around an article, means for tensioning the band after wrapping, means for holding the band against the pull of the tensioning means, means for releasing the tensioning means from the band, auxiliary means for holding the band under tension when the tensioning means is released, and means cooperating with said auxiliary holding means for severing the tensioned band and crimping the end of the succeeding band to prevent it from catching on another element of the machine or the overlap of the preceding band.

14. A machine of the character described comprising, means for wrapping band around an article, means for tensioning the band and overlapping portions thereof, and means for uniting the overlapped portions by electric welding, said welding means including, a plurality of elements carrying electrodes, and means for reciprocating the electrodes to and from the line of band feed and upwardly and downwardly in the line of band feed, said reciprocating means including a rock shaft, arms fixed to the rock shaft and connected to said electrode elements, a cam arm also fixed to said rock shaft, a driven cam in operative contact with said cam arm, a second rock shaft, an angle arm fixed to said second rock shaft, a driven cam in operative contact with one branch of said angle arm, at least one reciprocable plunger connected to the other branch of said angle arm and in operative contact with said electrode elements, and means for eliminating shock in the motion of said electrode elements, said shock eliminating means embodying a cam arm fixed to said second rock shaft, and a driven cam in operative contact with said last named cam arm, said last named cam being so shaped and positioned as to, in effect, act as a counterbalance to the effect of the cam that is in operative contact with one branch of said angle arm.

15. A machine of the character described comprising, means for wrapping band around an article, means for tensioning the band and overlapping portions thereof, and means for uniting the overlapped portions by electric welding, said welding means including, a plurality of elements carrying electrodes, and means for reciprocating the electrodes to and from the line of band feed and upwardly and downwardly in the line of band feed, said reciprocating means including a rock shaft, arms fixed to the rock shaft and connected to said electrode elements, a cam arm also fixed to said rock shaft, a driven cam in operative contact with said cam arm, a second rock shaft, an angle arm fixed to said second rock shaft, a driven cam in operative contact with one branch of said angle arm, at least one reciprocable plunger connected to the other branch of said angle arm and in op-

erative contact with said electrode elements, and means for eliminating shock in the motion of said electrode elements, said shock eliminating means embodying a cam arm fixed to said second rock shaft, and a driven cam

5 in operative contact with said last named cam arm, said last named cam being so shaped and positioned as to, in effect, act as a counterbalance to the effect of the cam that is in operative contact with one branch of said angle arm, and a spring in operative connection with the branch of said angle arm that is connected to the plunger for smoothing the action of the said angle arm.

16. In a machine designed and adapted to wrap metallic band around successive articles of varying size, means for feeding such band to the wrapping means, said 15 feeding means comprising, a source of band supply, driven means for drawing band from the source, and means for continuing said drawing means in operation following the wrapping of each article in order to provide a continuing slack excess of band between the drawing means and the wrapping means.

17. A machine as defined in claim 16, in which the band feeding means also includes means for discontinuing the operation of the drawing means when the excess of band reaches a predetermined amount.

18. A machine as defined in claim 17, in which the means for discontinuing the operation of the drawing means is governed by the band itself.

19. A machine as defined in claim 18, in which the band feeding means also includes means for stopping the 30 source of band supply when the operation of the drawing means is discontinued to prevent overthrow of the band.

20. In a machine designed and adapted to wrap metallic band around successive articles of varying size, means for feeding such band to the wrapping means, said 35 feeding means comprising, a band carrying reel, band feed rolls, means for driving at least one of the rolls, a unit activable by the proximity of the band itself, and means connecting the unit with the feed roll driving means for continuing the feed to maintain a slack excess 40 of band between the feed rolls and the wrapping means and for stopping the said driving means when the excess of band reaches a predetermined amount.

21. A machine as defined in claim 20, in which the band feeding means also includes means for connecting 45 the said unit with the band carrying reel to brake the reel when the driving means is stopped.

22. A machine as defined in claim 21, in which the said unit is electric, and in which the means connecting the unit with the feed roll driving means and with the 50 band carrying reel includes solenoid and clutch devices.

23. A machine of the character described comprising, means for wrapping band around an article, and means for tensioning the band after wrapping, said tensioning means including a gripper for seizing the band, means 55 for urging the gripper to closed position, means for reciprocating the gripper, and manually operable mechanism including a hand actuated lever connected with said urging means for temporarily opening the gripper for receiving the band.
